UNITED STATES PATENT OFFICE

149,123

DESIGN FOR A PHOTOGRAPHIC FILM VIEWER

Ira J. Grey, New York, N. Y.

Application January 25, 1947, Serial No. 136,417

Term of patent 3½ years

(Cl. D61—1)

To all whom it may concern:

Be it known that I, Ira J. Grey, a citizen of the United States of America and a resident of the city of New York, in the county of Kings and State of New York, have invented a new, original, and ornamental Design for a Photographic Film Viewer, of which the following is a specification, reference being had to the accompanying drawing forming a part thereof.

Fig. 1 is a top view of a photographic film viewer showing my design.

Fig. 2 is a bottom view thereof,

Fig. 3 is a rear view thereof, and

Fig. 4 is a front view thereof.

I claim:

The ornamental design for a photographic film viewer, substantially as shown.

IRA J. GREY.
